(57) **CLAIM**

The ornamental design for a high bay light fixture, as shown and described.

DESCRIPTION

FIG. 1 is a top perspective view of a high bay light fixture according to the present invention.

FIG. 2 is a bottom perspective view of the high bay light fixture illustrated in FIG. 1.

FIG. 3 is a top plan view of the high bay light fixture illustrated in FIG. 1.

FIG. 4 is a bottom plan view the high bay light fixture illustrated in FIG. 1.

FIG. 5 is a side elevation view the high bay light fixture illustrated in FIG. 1; and,

FIG. 6 is a front elevation view the high bay light fixture illustrated in FIG. 1.
